POLISHING APPARATUS FOR ROLLS

Paul K. Pisarcik, East Vandergrift, Pa.

Application September 14, 1940, Serial No. 356,784

17 Claims. (Cl. 51—253)

My invention relates to automatically operable roll polishing apparatus for polishing the rolls of a mill and especially a two high sheet mill, for example. The invention is particularly designed to do away with the laborious and unsatisfactory manual methods of polishing and/or treating the rolls as now very generally followed in commercial mill operations.

I am aware that mechanical polishing apparatus for polishing the rolls of mills of the character under consideration have been devised, but such apparatus have not proven entirely satisfactory when applied to and attempted to be employed in connection with such mills in comparison with the present invention.

My invention contemplates the employment of automatically operable polishing means designed for application to and for polishing either the lower or the upper roll or both rolls, of a two high mill; said means being capable of being used while the mill is in operation.

Among the objects of my invention are; the provision of a plurality of independent polishing stones adapted to be positioned adjacent a roll and extend across the major portion of the width or working surface of the roll to be treated; means for effecting a relatively slight lateral movement of the stones along the surface or working face of a roll, a new and improved construction enabling the polishing apparatus for either or both the lower and upper rolls to be connected with the coupling or coupling-box associated with the lower rolls of the mill; means for effecting simultaneous lateral movements of the stones for polishing both the lower and upper rolls; means for producing an arcuate or similar movement of the stones to effect a scrubbing action of the stones on the working face of a roll whereby a very efficient cleaning of the roll is accomplished; and new and improved means for effecting either a combined arcuate and lateral movement of the stones on the working face of a roll, or lateral movement only.

Other objects are, to provide new and improved means for automatically reversing the slight lateral movement of the stones and the stone carriers to provide a reciprocating movement of the polishing stones along the working face of a roll; and to provide a simple and efficient polishing apparatus that may be readily applied to a two high mill or the like of the usual construction.

Further objects are, to provide constructions enabling the polishing apparatus to be applied to a mill of any width; to save excessive wear on

the blocks or stones by proper counterweighting; to provide separate relatively small stones or blocks each covering only a small area of the roll thereby eliminating the need for applying high pressure which wears the rolls down; and the provision of means for varying the polishing action at certain points along the width of the rolls when necessary.

In the accompanying drawings which illustrate applications of my invention:

Fig. 1 is a side or end elevational view of a two high mill showing an embodiment of my invention associated therewith and particularly designed for polishing the lower or bottom roll of the mill;

Fig. 2, a front elevational view;

Fig. 3, a front elevational view of the mill showing an embodiment of my invention particularly designed for polishing the upper or top roll of the mill;

Fig. 4, an end elevational view of the form of Fig. 3;

Fig. 5, a view similar to Fig. 4 of the opposite end;

Fig. 6, a diagrammatic view showing several housings and several pairs of rolls and the connections between the lower rolls;

Fig. 7, a diagrammatic view particularly illustrating the arcuate movements of the stones;

Fig. 8, a view like Fig. 4 particularly showing the manner of connecting the connecting rods for the bottom and top polishing apparatus to a common pin on the eccentric strap;

Fig. 9, a detail view showing the mounting of one of the main levers with its stone holder; and

Fig. 10, a sectional detail view of the separable stone holder as carried by its lever arm.

Referring to the drawings the polishing apparatus embodying my invention is designed to be conveniently applied to a conventional two high rolling mill, each stand of which includes a housing 5, an upper roll 6 and a bottom roll 7.

In the form of Fig. 1, I have shown the polishing device or the polisher per se, positioned to operate on the lower roll 7 and in the form of Fig. 3, on the upper roll 6; in both cases the driving power is derived from the positively driven lower roll of the mill or stand.

Particularly referring first to the form of Figs. 1 and 2, 8 designates a coupling or coupling-box associated with a wobble *w* of the lower roll 7, and 9 an eccentric strap positioned on an actuating eccentric 9a of the coupling and having a two-part slotted lug with a pivot pin 10 carried thereby. An adjustable connecting rod

11 having a hook connection 11a for engagement with the pin 10, leads therefrom, to a bifurcated arm 12 to which the rod 11 is connected. Arm 12 is fixedly supported on a horizontally extending turnable or partially rotatable shaft 13 supported on apertured lugs 13a on the housing 5. It will be apparent that reciprocating movements of the pin 10, will, through the described connections, alternately turn shaft 13.

A characteristic and important feature of the present invention resides in means for imparting to the polishing stones or blocks an arcuate motion and corresponding scrubbing action while in contact with the working face or surface of the roll being treated. The means for effecting this scrubbing action include an upright roller arm 14 fixedly secured to shaft 13 designed to cooperate with the inclined slot of a cam-plate 15; and a plurality of lever arms 16, 16a, or more, extending downwardly and inwardly towards the surface of the lower roll 7. The upper end of the lever arm 16 as well as the lever arms 16a, etc. are each provided at one end with an adjustable weight w' and at their other ends, adjacent the surface of the lower roll, with means for supporting one or a number of sets of polishing blocks made up of single or independent plural polishing stones designated 19. It will be noted that the lever arms are connected, as by bar 16b, and that cam-plate 15 is integrally secured to or forms part of the first lever 16 and that the lever 16 and 16a, or additional similar levers, are pivotally connected to a framing member 17 at 18. Member 17 also acts as a supporting fulcrum for the lever arms 16 etc.

Connected with the lever 16 and extending horizontally therefrom, is the slotted connecting bar 16b designed to have the successive lever or levers 16a, etc. connected to it. The lever 16a is also pivotally connected to the framing member 17 as at 18 in a manner similar to the lever 16, as are also any additional levers.

Removable stone holders 51 having handles 52 are employed. These holders are respectively supported on plates 53 mounted on and carried by the ends of the levers 16 etc., and one of the plates 53 is suitably secured to its lever, as by a retaining lug to permit a slight turning movement so as to always assure the polishing stones having the desired surface contact with the roll.

Lever 16 is connected with and movable by the movement of cam 15, which latter arm in turn as above described is moved by the alternating rotation of shaft 13. The horizontally extending bar 16b to which the lever 16a is connected is secured to the lever arm 16. The movement of the lever 16 through said connecting bar 16b will thus move the one or more levers 16a with movements corresponding to the movement of lever 16, as actuated by cam 15.

Thus reciprocating action of bar 11 imparts alternating rotation to shaft 13 and its arm 14 in the slot of cam-plate 15. The cam-plate being directly connected with the adjacent lever arm 16 of the connected series of such arms, all of the several arms 16, 16a, etc. are moved laterally on their hinge or pivot mountings 18 of framing member 17.

By such mounting and resulting alternating back and forth movement of the stone supporting lower terminals of levers 16, 16a, etc. each lever terminal will thus move in a reversing series of back and forth arcuate paths d, with relation to pivoting connection 18, generally lengthwise of the roll, as indicated in Fig. 7.

The stone or block holders 51 are arranged so as to extend across the major portion of the width of the roll being treated. In the drawings I have shown a plurality of holders with two stones only in each holder. In practice however, for example, on a 36" roll I may employ five stones and two holders, two stones in one holder and three stones in another holder. For 44" rolls six stones may be employed in three holders 10 with two stones in each. For 48" rolls seven stones, two holders with two stones each therein and one holder with three stones. For 56" rolls eight stones, four holders with two stones each. For 60" rolls nine stones, three holders 15 with two stones each and one holder with three stones. For 68" rolls ten stones, five holders with two stones each.

In the form of Fig. 1 in addition to the arcuate movements, or scrubbing action, of the stones just described, I contemplate moving the holders and their stones laterally of the roll by means actuated through the turnable shaft 13.

As illustrated and as preferred, these means include a worm screw shaft 20 having a connecting element or arm 21 at one end for engagement with and for imparting relatively slow back and forth movement to the lever supporting member 17, and a ratchet or gear and pawl assembly including gear 22 the hub of which constitutes a worm nut on shaft 20, and pawls 23 and 51.

The rotation of worm shaft 20 is effected by means, including a bifurcated arm or lever 25 fixedly secured to shaft 13, a connecting rod 26 35 pivotally connected to the arm 25 at one end and at its opposite end to another bifurcated arm 27 at pivot point 28. The ratchet or gear 22 is disposed between the divided arms 27 and the pawls 23 are pivotally attached thereto.

30 designates U-shaped casing members located at opposite ends of the polishing devices, each being fastened to the housing 5. Adapted to operate within the U-shaped members 30, I provide carriages 31 into which projects at each side a stub shaft 32 connected to the reciprocating frame structure 17.

On the end of shaft 20 is a nut 33 which is slidably connected to an arm 34 pivoted on housing 5 at 35.

One end of the arm 34 is pivotally connected to an upright member 36. Arm 36 at its upper end is pivotally connected to a transversely extending arm 37 at 38, 37 in turn being pivoted to the housing 5 at 39.

It will be noted that this construction permits 55 a slight up and down movement of arm 37. Arm 37 at its opposite end is connected to a link 40, said link 40 engaging a link 41 which latter is secured to a barrel-like tubular structure 42. This structure 42 has two weight balls 43 disposed therein, for opposite tipping followed by gravitation of the balls. This barrel-like structure is also provided with bumper devices 44 adapted, when the barrel is tilted, to contact with another somewhat like structure 45 which also contains weight balls 46. Barrels 42 and 45 are respectively pivoted to the housing at 47 and 48 respectively, one spaced above the other as shown, for free tilting.

As above described, when the upper barrel is tilted by levers 34, 36, 37 it will actuate barrel 45 reversely with reversed tension on chains 49 and 50 for the purpose of freeing pawl 23 from the ratchet 22, and simultaneously place a pawl 75 51 into engagement with the ratchet 22.

Thus it will be evident that a reversal of arms 16, 16a, etc. and the reverse movement of the polisher elements and carriage is accomplished, by member 17 as controlled by alternating forward and back feed of shaft 20 by the ratchet and pawl mechanism under control of the hub nut of ratchet 22.

In the form of Figs. 3, 4, 5 and 8, I have particularly shown polishing apparatus designed for treatment of the upper roll 6a instead of the lower roll 1a. In this construction 8a designates a coupling or coupling-box of the character shown in the construction of Fig. 1 and as in the form of Fig. 1 the coupling-box 8a is associated with a wobble w of the lower roll 1a. This form also includes an eccentric strap 9 positioned on the coupling and carrying a pin 10a.

An adjustable connecting rod 11b having a hook connection with the pin is shown as in the form of Fig. 1.

The opposite end of the adjustable connecting rod 11b is connected with a depending member 27a, corresponding somewhat to the member 21 of Fig. 1; said rod being pivotally connected to member 27a at the pivot point 24a.

In the form of Figs. 3-4, the polishing stones 19a are designed to have a lateral movement only relative to the roll being treated, therefore the means shown in the form of Fig. 1 for accomplishing an arcuate scrubbing action are omitted. In this form of my invention, however, I contemplate using a plurality of polishing stone holders with separate and independent stones 19a carried in the holders as in the form of Fig. 1.

In this form 20a designates the worm shaft having the gear and ratchet assembly substantially of a character shown in Fig. 1 associated therewith, the ratchet hub engaging the shaft as the worm nut. The rotation of the worm shaft 20a is effected in this instance by means of the double arm 27a attached as aforesaid to the pin 10a and actuated by the connecting rod 11b.

As shaft 20a is alternately moved forwardly and backwardly by the threaded hub of the ratchet and pawl mechanism, the entire series of stones 19a is correspondingly moved lengthwise of the upper roll by arm 21a and shaft 11a.

The construction and operation of such polishing means for the upper roll is applied, as shown in Figs. 3, 4, 5 and 8, to the descending face of the roll at the receiving side of the mill, generally similar to the stone location at the descending face of the lower roll at the delivery side, as in Figs. 1 and 2.

Both constructions derive their actuating power from the eccentric strap 9 and its pin 10a and an oppositely extending connecting rod 11b having a similar hook connection with the pin.

The outer terminal of rod 11b is pivoted at 24a to the ends of arms 27a having the pawls 23a and 51a engageable with the ratchet gear 22a, the hub of which is threaded for turning engagement with worm shaft 20a.

Also, a movable worm nut 33c on shaft 20a is pivotally connected to an arm 36a at 35a. Such member likewise engages arm 37a at 38a, arm 37a being pivoted as at 39a. Arm 37a, like arm 37, is connected to a link 41a secured to the tubular member 42a having the gravitating balls 43a, for opposite tipping. In the same manner the bumper devices 44a contact the tubular lever arm 45a for tipping same, with its gravitating balls 46a. Tipping of arm 45a effects reverse action of chains 49a and 50a with corresponding pawl disengagement and engagement and rever-

sal of movement of shaft 20a. Shaft 11a and the longitudinal series of stones 19a with their holders, refuse collectors, etc. is alternately moved lengthwise by arm 21a the end of which is in nut engagement with threaded shaft 20a.

In this manner the entire series of polishing stones 9 are moved longitudinally in a straight line alternately back and forth across the face of the upper roll, in rotation. Shaft 20a is suitably supported in bearings 30a.

As shown in Figs. 3, 4 and 5 variable pressure of the longitudinally movable stones is controlled by temper springs 54 surrounding rods 55 engaging lever arms 56 secured to the ends of shaft 11a. By graduating the springs more or less, the pressure of the stones against the roll face may be adjusted as desired.

What I claim is:

1. In an automatic polisher for a roll of a two high mill, the combination with the coupling of the lower roll and an eccentric strap thereon, a plurality of independent polishing stones positioned adjacent a roll and extending across the major portion of the width of the roll, holders for the stones, and means including a pivotal mounting for the holders, a longitudinally movable shaft engaging said mounting for imparting main back and forth movements thereto, an alternating rotatable shaft having cam connection with the holders for imparting minor pivoting movements thereto during such main movements, and operating means for said shafts connecting them with the eccentric strap for effecting a combined lateral and arcuate movement of the stones on the surface of the roll.

2. In an automatic polisher for a roll of a two high mill, the combination with the coupling of the lower roll and a movement imparting element thereon, a plurality of independent polishing stones positioned adjacent a roll and extending across the major portion of the width of the roll, holders for the stones, a main alternately movable pivoting support for the holders, and means including a rotatable shaft, a cam-plate engaged thereby, a pivotal connecting lever mounted on said support between the cam-plate and the holders, and driving means between the said shaft and the movement imparting element on the coupling for effecting an arcuate movement of the stones on the surface of the roll.

3. In an automatic polisher for a roll of a two high mill, the combination with the coupling of the lower roll, of an eccentric thereon, a plurality of independent polishing stones positioned adjacent a roll and extending across the major portion of the width of the roll, holders for the stones, and means connecting the holders and the coupling for effecting combined major lateral and minor arcuate movements of the stones on the surface of the roll, said means including a rotatable shaft, a drive rod connecting the shaft and the eccentric, a cam-plate connected with the holders, said rotatable shaft having an arm cooperating with the cam-plate for effecting said minor arcuate movements, a second shaft and means for imparting alternating longitudinal movement thereto, a holder support actuated thereby, and a pivotal connection between the holder support and holders.

4. In an automatic polisher for a roll of a two high mill, the combination with the coupling of the lower roll and an eccentric thereon, a plurality of independent polishing stones positioned adjacent a roll and extending across the major portion of the width of the roll, a laterally mov-

able supporting member, stone holders connected with and spaced from the supporting member, means pivotally connecting the member and holders, means for effecting a combined arcuate and lateral movement of the stones on the roll including a rotatable shaft, a connection between the eccentric and the rotatable shaft, and a second longitudinally movable shaft driven through the first shaft and connected with the supporting member for moving the stone holders laterally of the roll.

5. In an automatic polisher for a roll of a two high mill, the combination with the coupling of the lower roll and an eccentric thereon, a plurality of independent polishing stones positioned adjacent a roll and extending across the major portion of the width of the roll, a laterally movable supporting member, stone holders connected with and spaced from the supporting member, means connecting the member and holders, means for effecting a combined arcuate and lateral movement of the stones on the roll including a rotatable shaft, and means connected therewith effecting continuous minor arcuate movements to the stone holders, a connection between the eccentric and the rotatable shaft, a second longitudinally movable shaft driven through the first shaft and connected with the supporting member for moving the stone holders laterally of the roll, and means associated with the second shaft for effecting major reciprocation of the polishing stones relative to the working surface of the roll.

6. Means for polishing a roll of a two high mill by moving a polishing element across the face of the roll consisting of a support for the element, an alternately acting longitudinally movable screw shaft, means connecting it with the polishing element support for corresponding alternating main back and forth movements, a ratchet wheel having a hub in threaded engagement with the shaft, a pawl-supporting holder pivoted to the ratchet and having a pair of alternately acting pawls, a midway pivoted tilting beam having gravitating weights and oppositely acting connections with the pawls for alternating pawl engagement with the ratchet, means effecting tilting of the beam operatively connected with the screw shaft, and means connecting the pawl-supporting holder reciprocably with actuating means carried by one of the rolls.

7. Means for polishing a roll of a two high mill by moving a polishing element across the face of the roll consisting of a support for the element, an alternately acting longitudinally movable screw shaft, means connecting it with the polishing element support for corresponding alternating main back and forth movements, a ratchet wheel having a hub in threaded engagement with the shaft, a pawl-supporting holder pivoted to the ratchet and having a pair of alternately acting pawls, a midway pivoted tilting beam having gravitating weights and oppositely acting connections with the pawls for alternating pawl engagement with the ratchet, means effecting tilting of the beam operatively connected with the screw shaft, an eccentric actuated by the mill, and means connecting the pawl-supporting holder with the eccentric.

8. Means for polishing a roll of a two high mill by moving a polishing element across the face of the roll consisting of a support for the element, an alternately acting longitudinally movable screw shaft, means connecting it with the polishing element support for corresponding alternating

main back and forth movements, a ratchet wheel having a hub in threaded engagement with the shaft, a pawl-supporting holder pivoted to the ratchet and having a pair of alternately acting pawls, a midway pivoted tilting beam having gravitating weights and oppositely acting connections with the pawls for alternating pawl engagement with the ratchet, means effecting tilting of the beam operatively connected with the screw shaft, an eccentric mounted on one of the rolls having a surrounding strap, and a connecting rod between the strap and the pawl holder for actuating the ratchet in one direction or the other when either pawl is in engagement therewith.

5 9. Means for polishing a roll of a two high mill by moving a polishing element across the face of the roll consisting of a support for the element, an alternately acting longitudinally movable screw shaft, means connecting it with the polishing element support for corresponding alternating main back and forth movements, a ratchet wheel having a hub in threaded engagement with the shaft, a pawl-supporting holder pivoted to the ratchet and having a pair of alternately acting pawls, a midway pivoted tilting beam having gravitating weights and oppositely acting connections with the pawls for alternating pawl engagement with the ratchet, means effecting tilting of the beam operatively connected with the screw shaft, an eccentric mounted on one of the rolls having a surrounding strap, and a connecting rod between the strap and the pawl holder for actuating the ratchet in one direction or the other when either pawl is in engagement therewith.

mounted between its ends on said reciprocably moving member, means for moving the lever laterally and alternately on its pivotal mounting, an outer counterweight on the free end of the lever, a removable stone holder having a handle on the inner opposite end of the lever, and a support for the stone holder on the inner active end of the lever.

13. In roll polishing apparatus, a reciprocably moving lever-supporting member, a stone supporting lever pivotally mounted between its ends on said reciprocably moving member, means for moving the lever laterally and alternately on its pivotal mounting during each major main back and forth movement, means for moving the lever on its supporting member in minor arcuate multiples of such main movements, a slotted cam on the lever, an alternately rotatable shaft having an actuating arm therefor, means for actuating the shaft, a stone holder support on the inner end of the lever adjacent the roll being polished, and a stone holder having a handle for placement of the holder on said support.

14. In an automatic roll polisher having a stone supporting lever and a reciprocating member pivotally engaging the lever, a longitudinally movable worm shaft for moving said member, an actuating ratchet wheel therefor, a pawl-carrying frame pivoted on the ratchet wheel provided with a pair of single acting pawls, a midway pivoted tilting beam having terminal flexible connections with each pawl, and means actuated by the worm shaft for reversely tilting the beam to change the operative relations of the pawls to reverse the direction of longitudinal movement of the worm shaft.

15. In an automatic roll polisher having a stone supporting lever and a reciprocating member pivotally engaging the lever, a longitudinally movable worm shaft for moving said member, an actuating ratchet wheel therefor in threaded engagement with the worm shaft, a pawl-carrying frame pivoted on the ratchet wheel provided with a pair of single acting pawls, a tilting beam having flexible connections with each pawl, a lever

and means controlled thereby for tilting the beam, and a nut on the worm shaft operatively connected with said lever for reversely tilting the beam to change the operative relations of the pawls to reverse the direction of movement of the worm shaft.

16. Means for polishing a roll of a two high mill by moving a polishing element across the face of the roll with alternating arcuate movement thereof consisting of a pivotal support for the element, a longitudinally movable alternately acting screw shaft, means connecting it with the polishing element support for corresponding alternating main back and forth movements, a ratchet wheel having a hub in threaded engagement with the shaft, a pawl-supporting holder pivoted to the ratchet wheel and having a pair of alternately acting pawls, a midway pivoted tilting beam having oppositely acting connections with the pawls for alternating pawl engagement with the ratchet, and means operatively connected with the screw shaft for effecting tilting of the beam and reverse movement of the screw shaft.

17. Means for polishing a roll of a two high mill by moving a polishing element across the face of the roll with alternating arcuate movement thereof consisting of a pivotal support for the element, a longitudinally movable alternately acting screw shaft, means connecting it with the polishing element support for corresponding alternating main back and forth movements, a ratchet wheel having a hub in threaded engagement with the shaft, a pawl-supporting holder pivoted to the ratchet wheel and having a pair of alternately acting pawls, a midway pivoted tilting beam having oppositely acting connections with the pawls for alternating pawl engagement with the ratchet, lever mechanism operatively connected with the tilting beam, and a nut threaded on the screw shaft and in operative connection with the lever mechanism for tilting the beam.
